(57) **CLAIM**

The ornamental design for a tire tread, as shown and described.

DESCRIPTION

FIG. 1 is a perspective view of a tire tread, it being understood that the tread pattern repeats uniformly throughout the circumference of the tire.

FIG. 2 is a front elevation view thereof. A top plan view, a bottom plan view and a rear elevation view are identical with the front elevation view.

FIG. 3 is a left side elevation view thereof. A right side elevation view is identical with the left side elevation view; and,

FIG. 4 is an enlarged fragmentary front view thereof.

The portion of the article shown in broken lines is for illustrative purpose only and forms no part of the claimed design.
